UNITED STATES PATENT OFFICE.

LYLE C. EISENHART AND WILLIAM A. LEWIS, OF SILVER CITY, IDAHO.

BOOK-REST.

1,323,586.

Specification of Letters Patent.

Patented Dec. 2, 1919.

Application filed August 21, 1919. Serial No. 318,978.

To all whom it may concern:

Be it known that we, LYLE C. EISENHART and WILLIAM A. LEWIS, citizens of the United States, residing at Silver City, in the county of Owyhee and State of Idaho, have invented certain new and useful Improvements in Book-Rests, of which the following is a specification.

The invention relates to supporting means for books and aims to provide a device of this character involving a novel structure and arrangement of parts, whereby the device is adjustable to books of different sizes and to suit the convenience of the person.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

The drawings hereto attached illustrate the preferred form of my invention and on reference thereto:

Figure 1 is a top plan view of a book rest or support embodying the invention.

Fig. 2 is a sectional detail on the line 2—2 of Fig. 1, parts being broken away.

Fig. 3 is a vertical longitudinal section on the line 3—3 of Fig. 1.

Fig. 4 is a transverse section on the line 4—4 of Fig. 1.

Fig. 5 is a detail view of a portion of the device as seen from below.

Fig. 6 is a sectional detail on the line 6—6 of Fig. 4.

Fig. 7 is an enlarged sectional detail on the line 7—7 of Fig. 5.

Corresponding and like parts are referred to in the following description and indicated in the several views of the drawings by like reference characters.

The device comprises a base, which partakes of the nature of a track, since the parts mounted thereon are movable. The base includes two longitudinal members 1 which are disposed in parallel relation and are suitably connected by cross ties 2, which preferably consist of rods. Each of the longitudinal members 1 is slotted throughout its length, as shown most clearly in Figs. 2 and 3. The rear member 1 is provided with feet 3, whereby it is supported in a slightly higher plane than the front member, with the result that the book rest is

inclined to the horizontal in substantially the same manner as the top of a desk which is sloped downwardly from rear to front.

The rest proper is mounted upon the base to move longitudinally thereon and comprises a middle section A and end sections B. The end sections B are adjustable to admit of the length of the rest being varied according to the size of the book to be supported thereby.

The middle section A is provided with front and rear rollers 3 which are adapted to engage the longitudinal members of the base.

The end sections B are similarly provided with front and rear rollers 4 which likewise engage the members.

1. The several rollers 3 and 4 are mounted in the slots of the members 1 and are carried by hangers which embrace the respective members 1 and are attached to the respective sections A and B.

The middle section A is provided at its longitudinal or top and bottom edges with guides 5 which receive opposite edge portions of the respective end sections B.

Any suitable fastening means may be provided for securing the sections B in the adjusted position.

These fastening means are indicated at 6 and may consist of hand screws or other clamping means.

The guides 5 may be provided in any manner and preferably consist of folded edge portions of the section A, the same being preferably constructed of sheet metal.

The sections B are likewise formed of sheet metal and are slidable in the guides 5 to admit of the length of the book rest being varied to

be supported thereon.

The arm rest comprises similar or like parts which are adjustably connected with the book rest so as to be moved laterally.

Each part of the arm rest is a duplicate of the other, hence a detailed description of one will suffice for a full understanding of both.

The arm rest comprises a lower section 7, an end portion 8 and a top section 9.

The lower section 7 has its edge portions bent upwardly, thence laterally in an outward direction to engage guides 10 and 10^a on the middle section A of the book rest.

The guides 10 are at the ends of the section A and are formed by folding edge portions thereof.

The guides 10^a are formed at the edges of a strip which is secured at a middle point to the section A.

The section 7, like the section A has portions cut therefrom to lighten the structure.

Suitable means are

provided for holding the parts of the arm rest in adjusted position. As shown, springs 11 are attached to the section A and frictionally engage the section 7, as indicated most clearly in Figs. 4 and 7. The springs 11 are secured at their ends to edge portions of the section A and the middle portion of each is deflected downwardly so as to engage the section 7 and retain it in 10 adjusted position.

The parts 7, 8 and 9 are hingedly connected and as a result, the top section 9 may be adjusted to any relative plate to adapt the same to the thickness of the book, so that 15 the arm may be on a level with the top page of the book. The provision of the intermediate section 8 provides for the section 9 adapting itself to the thickness of the book, so as to rest on the top thereof. These sections may be hingedly connected in any manner and as shown adjacent edge portions are rolled and cutaway to form matching 20 knuckles through which pintle rods pass to pivotally connect the sections.

25 The arm rest is extensible with the hook rest and for this purpose sections 12 are adjustably connected with the top sections 9, so as to be moved in or out to vary the length of the arm rest to suit the length of 30 the book when adapting the device to a particular length. The sections 12 are supported in guides on the sections 9 and which guides may form a part of the sections 9 and constitute folded edge portions thereof.

35 A device constructed in accordance with the invention is adapted to be readily adjusted to books of different sizes, both as to length and thickness, so that the arm may be supported on a level with the top of the 40 book when the latter is open and the arm rest may be coextensive with the length of the book rest. The structure is such as to admit of the device being reduced to compact form to occupy a minimum amount of 45 space when not required for immediate use.

The foregoing description and the drawings have reference to what may be considered the preferred, or approved form of our invention. It is to be understood that 50 we may make such changes in construction and arrangement and combination of parts, materials, dimensions, et cetera, as may prove expedient and fall within the scope of the appended claims.

55 Having thus fully described our invention, what we claim as new and desire to secure by Letters Patent is:—

60 1. A book rest, comprising movable sections adapted to admit of the length of the rest being varied and an arm rest comprising movably related sections to admit of

the length of the arm rest being made to conform to the length of the book rest.

2. A book rest, comprising movable sections to admit of the length of the rest being varied and an arm rest adjustably connected with the book rest and comprising movable sections to admit of the length of the arm rest being made to conform to the length of the book rest. 65 70

3. A book rest, comprising a base including spaced longitudinal members which are slotted throughout their length, a middle section, end sections slidably engaging the middle section and independent supporting 75 means for the middle and end sections engaging the slots of the respective longitudinal members of the base.

4. In a book rest, an arm rest, comprising a lower, a top and an end section, the several sections being hingedly connected to admit of the top section adapting itself to the top of the book so that the arm may be on a level therewith. 80

5. In combination with a book rest, an arm rest, comprising a lower section having adjustable connection with the book rest, an outer end section hingedly connected with the lower section and a top hingedly connected with the end section and adapted to conform to the level of the top of a book so that the arm may be supported on a level therewith. 85 90

6. In combination with a book rest, an arm rest, comprising a lower section having adjustable connection with the book rest, an outer end section hingedly connected with the lower section and a top hingedly connected with the end section and adapted to conform to the level of the top of a book so that the arm may be supported on a level therewith and an extensible section adjustably connected with the top section to admit of varying the length of the arm rest. 95 100

7. In a book rest, a middle section, end sections adjustably connected with the middle section and an arm rest comprising like parts, each consisting of a lower section adjustably connected with the middle section of the book rest to be moved in and out, an end section hingedly connected to the lower section, a top section hingedly connected to the end section and an adjustable section movable relatively to the top section. 110

In testimony whereof we affix our signatures in presence of two witnesses.

LYLE C. EISENHART.
WILLIAM A. LEWIS.
